UNITED STATES PATENT OFFICE

98,917

DESIGN FOR A BUTTON

Leonard R. Carley, Watertown, Conn., assignor
to The Patent Button Company, Waterbury,
Conn., a corporation of Connecticut

Application December 4, 1934, Serial No. 54,262

Term of patent 14 years

To all whom it may concern:

Be it known that I, Leonard R. Carley, a citizen of the United States, residing at Watertown, in the county of Litchfield and State of Connecticut, have invented a new, original, and ornamental Design for Buttons, of which the following is a specification, reference being had to the accompanying drawing forming part thereof, in which:

Fig. 1 is a top plan view of a button on an enlarged scale showing my new design;

Fig. 2 is a side elevation thereof;

Fig. 3 is a sectional view thereof; and
Fig. 4 is a bottom plan view thereof.

The primary features of the button are an annular portion and an intermediate dome portion of less thickness than the annular portion, the upper surface of said dome portion being stippled.

I claim:

The ornamental design for a button, as shown and described.

LEONARD R. CARLEY.
